UNITED STATES PATENT OFFICE.

LOUIS W. BUTLER, OF NEW YORK, N. Y.

AUTOMATIC FOCUSING DEVICE.

1,142,767.

Specification of Letters Patent. Patented June 8, 1915.

Application filed January 25, 1913. Serial No. 744,146.

To all whom it may concern:

Be it known that I, LOUIS W. BUTLER, a citizen of the United States, and a resident of the city of New York, borough of Brooklyn, in the county of Kings and State of New York, have invented a new and Improved Automatic Focusing Device, of which the following is a full, clear, and exact description.

10 My invention relates to a device adapted for use on almost any kind of projecting apparatus for the sake of making enlarged images of given objects. It is especially designed for the purpose of making enlargements of negatives and it comprises essentially a holder for an object which is to be enlarged, a focusing device, and a screen on which the object to be enlarged is focused in the well-known way. This screen may be in 15 the form of a holder for a sensitized plate or film on which the enlargement is to be made. These parts are mounted so as to be relatively movable, and I employ in conjunction therewith a controlling device so constructed 20 that the relative movements of the parts in question are regulated in such a way that when one of the parts is moved the relative position of one or more of the remaining parts is so changed that the screen or plate 25 holder always remains in focusing relation. All the operator has to do, therefore, is to move one of the parts the required degree, this depending on the amount of enlargement that is desired.

30 Reference is to be had to the accompanying drawings forming a part of this specification, in which the same characters of reference indicate the same parts in all the views.

35 Figure 1 is a vertical longitudinal sectional view of my invention on the line 1—1 of Fig. 2; Fig. 2 is a horizontal sectional view on the line 2—2 of Fig. 1; Fig. 3 is a top plan of part of the controlling mechanism; Fig. 4 is a bottom plan of the same; Fig. 5 is a sectional view on the line 5—5 of Fig. 3; Fig. 6 is a sectional view on the line 6—6 of Fig. 3; and Fig. 7 is a diagrammatic view showing the shape of part of the 40 controlling mechanism.

45 My invention comprises a base 1 which may be the base of any kind of projecting or photographing apparatus, and on this base 1 I mount an object holder 2 and a lens holder 50 3 carrying a suitable number of lenses enclosed in a casing 4. This lens holder is lo-

cated between the object holder 2 on the one hand and a frame shown at 5 on the other, this frame serving as a screen on which the focusing is done, or serving to hold the plate 60 or film on which the enlargement is to be made. In the form shown in the drawings the screen 5 is fixed, but the base is provided with rails or guides 6 on which the lens holder and the object holder are movably 65 mounted so that the distance of these two parts from each other and from the member 5 can be increased or decreased at will.

70 I control the movements of the object holder and the lens holder 3 by means of mechanism which is normally located between these parts and fixed with reference to the lens holder by means of a bar or other convenient form of support on which the controlling device is carried. This controlling 75 device comprises essentially a plate 8 in which is formed a spiral cam slot 9; and the plate 8 is provided with a hub by means of which it is fixed upon a spindle 10. This spindle 10 is mounted in bearings formed in 80 plates 11 which are secured together by suitable bolts but are held a suitable distance apart by means of spacing sleeves 12 surrounding these bolts and located between the plates. The plate 8 will be located near 85 the bottom plate, and secured to the shaft 10 just below the upper plate is a gear wheel 13. This gear wheel 13 is engaged by a pinion 14 on a spindle 15 having a bearing in the upper plate and projecting above this plate 90 and carrying on its upper end another pinion 16 which engages a rack 17. This rack 17 is fixed to the base 1.

95 The above parts are carried on the bar 7 by providing this bar with arms or projections and fastening the same to the upper plate 11. Of course any other convenient method of attaching the frame comprising the plates 11 to the lens holder 3 may be employed.

100 The cam slot 9 actuates a stud or bolt 18 having an anti-friction sleeve 19 at its upper end and carrying on its lower end a pinion 20. This pinion 20 actuates a rack bar 21 secured to the object holder 2 and mounted 105 to slide in suitable openings carried by the plates 22 which project from the bottom of the lower plate 11. This pinion also engages a rack 23 which is fixed with respect to the lower plate 11, and it will be seen that 110 when the cam slot moves the stud 18 the pinion 20 will turn because of its engagement

with the fixed rack 23, and transmit a greater degree of movement to the movable rack 21. This fixed rack 23 and pinion 20 constitute in effect a multiplying arrangement, and I prefer to mount this pinion on a sliding plate 25 which serves as a support therefor.

The rack 23 is secured to the lower plate 11 by means of suitable spacing devices 24, 0 these spacing devices comprising a pair of plates which extend crosswise of the lower face of the lower plate 11 and are recessed to receive the plate 25 in which the stud 18 is carried. They also include Fig. 5 a plate 15 25' which extends longitudinally from one of the cross-pieces 24 to the other, thus forming a sort of guideway in which the plate 25 moves. This plate 25 will normally move about one-half of the distance traveled 20 by the rack bar 21 whenever the cam actuates the pinion 20. The rack 23 may be provided with lugs 26 which are slotted, and it may be secured to the lower plate 11 by means of screws 27. These slotted lugs 25 permit the adjustment of the rack 23 toward and from the rack 21.

Any suitable arrangement for inclosing the lens casing 4 and providing a dark chamber into which rays of light pass to be focused on the sensitized plate carried by the screen 5 may be employed. I show ordinary folds of cloth 28 on Fig. 1 for this purpose.

In order to project an enlarged image of 35 an object mounted in the holder 2, it is only necessary to slide the lens holder 3 back and forth along the rail 6. Through the racks and pinions above described motion will be transmitted to the holder 2, and this motion 40 will, because of the shape of the cam slot 9, be just enough to keep the parts in all positions in correct focusing relation with respect to the fixed screen 5.

The shape of the slot 9 in plate 8 is plotted in Fig. 7 and shown in detail in Figs. 3 and 4, the same acting as a cam on the spindle 19, whereby the focusing may be controlled so as to enlarge an image to several times the size of the object. The shape of 50 this slot must of course be proportioned in accordance with the size of the various gears and pinions hereinafter fully described so that the lens and the object will be moved toward or from each other for continually 55 maintaining the object in focus. Arranged on the slot as shown in Fig. 7 are a plurality of points designated as *a*, *b*, *c*, *d*, *e*, *f*, *g*, *h* and *i*, these being arranged on the slot as a matter of convenience for indicating when 60 the enlargement has reached a certain size. For instance, a double size or triple size. These distances may be secured by any suitable means, as, for instance, by a mathematical calculation or by plotting the same 65 directly upon the cam, the particular

method of securing these distances not forming any part of the present invention. If the stud 18 be located at the point *a* and the cam then turned so as to bring the slot into such position that the stud will be located at the point *b*, the size of the object or negative will be doubled. If further movement is effected so as to bring the slot into such position that the stud 18 will be located at the point *c*, the negative will be 75 enlarged three times and so on up to the point *i*, where it will be enlarged nine times.

Of course I may employ my invention for making images of any object, as it is by no means restricted to the enlargement of negatives. Instead, almost anything that is to be projected might be located in the holder 2.

As stated above, I am enabled to control the focusing for an enlarged image up to nine times the size of the object, and by increasing the dimensions of the cam I can control the focusing so as to produce an enlargement of a given object up to any number of times the size thereof. The movement of the lens to or from the screen one 85 focal length will cause a movement of the object holder which movement will be in proper proportion to the movement of the lens. Suitable multiplying gears and cams are provided for causing a proper movement 90 of the object holder in relation to the lens for maintaining the object holder a proper distance from the lens at all times 95 for presenting a proper focus.

It will be seen that when the controlling 100 device moves with the lens holder 3 the pinion 16 is turned by the fixed rack 17, and it will be readily understood that the resultant movement of the rack 21 and the object holder 2 will be due both to the cam slot and 105 the bodily movement of the disk in which the cam slot is formed. It is of course to be understood that the rack 17 will be made as long as is required to produce the desired results. It may extend the full length 110 of the base 1 if required.

When it is desired to change from a copying factor of one, the lens holder is moved away from the screen one inch, and this movement causes the various gears heretofore described, together with the cam, to transmit motion to the object holder for causing the same to move a proper distance 115 for maintaining the object therein properly in focus. This distance is one half an inch to the right as the parts are arranged in Fig. 2 of the drawings, whereby the lens will be three inches from the screen and the object holder four and one half inches 120 from the screen. As the lens has moved away from the screen 5, the same carries all of the gear wheels heretofore mentioned and in this movement causes the pinion 16 to rotate. This rotation is sufficient for transmitting a proper movement to the cam 8 for 125 130

causing the cam to move one eighth of a revolution, such movement of the cam being in a counter-clockwise direction, whereby the object holder is moved one half of an inch to 5 the left by the cam while the entire structure is being moved one inch to the right, thus resulting in a one half inch advance of the object holder. If the cam 8 were stationary, the pinion 20 would not rotate and 10 consequently the object holder would be moved the same distance as the lens, but by reason of the counter-clockwise rotation of the cam when the lens is moved to the right, the object holder is given a reverse movement according to the shape of the cam which, in a change from a copying factor 15 of one to a copying factor of two, is one half inch with the particular lens described. The shape of the slot of the cam from *b* to *a* 20 (Fig. 7) is such as to maintain the proper distance between the lens and the object holder for maintaining the focus at all points so that the device can be moved so as to have a copying factor of one, two or more, 25 or a copying factor of, for instance, one and one half or any other fraction desired.

I desire to have it understood that the above description is illustrative only and I do not care to be limited to the exact arrangement or details shown and described, 30 but reserve to myself the right to make such changes in the shape, size and arrangement of the parts as fairly fall within the scope and spirit of my invention.

Having thus described my invention, I claim as new and desire to secure by Letters Patent:

1. The combination of a screen, a lens holder and an object holder, guides on which 40 the lens holder and the object holder can be mounted so as to be movable toward and from the screen, a fixed rack, a rack connected to the object holder, and means carried by the lens holder and engaging said racks 45 to control the movements of the lens holder and object holder to keep the screen always in focusing relation.

2. The combination of a screen, a lens holder and an object holder, means for 50 mounting the object holder and the lens holder so that the same can be moved toward and from the screen, a fixed rack, a rack connected to the object holder, a pinion, and a cam actuated thereby to transmit

relative movement to the rack connected to 55 the object holder, said cam and said pinion being carried by the lens holder, said pinion meshing with said fixed rack, said cam being shaped to cause the lens holder and the object holder to be moved to such an extent 60 with respect to each other as to keep the screen always in focusing relation.

3. The combination of a screen, a lens holder, an object holder, means for mounting the lens holder and object holder to be 65 moved toward and from the screen, a fixed rack, a pinion and a cam actuated thereby, said pinion and said cam being carried by the lens holder, said pinion being actuated by said fixed rack, a rack carried by the object holder, and a multiplying device between said cam and said second-named rack, 70 said cam being shaped so as to cause the movement of the object holder with respect to the movement of the lens holder when 75 the latter is moved to keep the screen always in focusing relation.

4. The combination of a screen, a lens holder, an object holder, means for mounting said object holder and lens holder in 80 position to be moved toward and from the screen, a fixed rack, a rack connected to the object holder, a pinion, means actuated by said fixed rack for rotating said pinion, a gear wheel actuated by said pinion and a 85 slotted cam actuated by said gear wheel, said pinion, gear and cam being carried by the lens holder, a spindle actuated by the cam, a pinion on said spindle, said spindle and said pinion thereon also being carried 90 by the lens holder, a rack meshing with said last mentioned pinion carried by said lens holder for causing a rotation of said pinion when the lens holder is moved, the first-named pinion engaging and receiving movement from the fixed rack for rotating said 95 gear wheel, the said slotted cam being shaped to cause the object holder to be so moved with respect to the lens holder when the lens holder is moved, as to keep the 100 screen always in focusing relation.

In testimony whereof I have signed my name to this specification in the presence of two subscribing witnesses.

LOUIS W. BUTLER.
